(57) **CLAIM**

The ornamental design for a pet vacuum groomer as shown and described.

DESCRIPTION

FIG. 1 is a perspective view of a pet vacuum groomer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a pet vacuum groomer with different grooming heads; and,

FIG. 10 is another perspective view thereof.

The dash-dash broken lines in the drawings depict portions of the pet vacuum groomer that form no part of the claimed design. The additional broken lines seen in FIGS. 9 and 10 depict environment, and form no part of the claimed design.
